UNITED STATES PATENT OFFICE.

WARREN M. SMITH, OF BOROUGH OF PROSPECT PARK, PENNSYLVANIA,
ASSIGNOR TO JOHN A. BRILL, OF PHILADELPHIA, PENNSYLVANIA.

METALLIC CAR.

No. 852,808.

Specification of Letters Patent.

Patented May 7, 1907.

Application filed September 17, 1906. Serial No. 336,010.

To all whom it may concern:

Be it known that I, WARREN M. SMITH, a citizen of the United States, and a resident of the borough of Prospect Park, county of Delaware, and State of Pennsylvania, have invented a new and useful Improvement in Metallic Cars, of which the following is a specification.

The object of my invention is to provide an improved metallic car with large windows, which is adapted for street railway use, and commonly known as a "semi-convertible" car. This object is accomplished by my invention, as will appear below.

For a more particular description of my invention reference is to be had to the accompanying drawings, forming a part hereof, in which:

Figure 1 is a sectional view of the side of a car embodying my invention. Fig. 2 is an enlarged sectional view of the roof structure and adjacent parts shown in Fig. 1. Fig. 3 is a section view of a brace or sleeve. Fig. 4 is a side elevation of one end of the sleeve. Fig. 5 is a detailed view showing a portion of the roof structure. Fig. 6 is a plan view of a portion of the wall of a car and a channel carline secured thereto. Fig. 7 is a sectional view taken on the line 7—7 of Fig. 12. Fig. 8 is an enlarged perspective view, partially in section, of a portion of the side of a car. Figs. 9 and 10 are perspective views showing portions of the stanchions or posts. Fig. 11 is a sectional view showing portion of the upper roof or clear story. Fig. 12 is a sectional view showing the upper portion of the walls and roof of the car. Figs. 13 and 14 are enlarged detailed views of the ventilators and the car structure related thereto. Fig. 15 shows a stanchion below the parts shown in Fig. 12; the sashes and a portion of the car being shown in section. Fig. 16 is an enlarged view showing the structure below what is shown in Fig. 15. Fig. 17 is a sectional view taken on the line 17—17 of Fig. 15, looking in the direction of the arrows. Fig. 18 is an enlarged view of the window sill structure. Figs. 19, 20 and 21 show details of construction.

Throughout the various views of the drawings similar reference characters designate similar parts.

My improved car 1 is provided with the usual clear story roof 2, lower roof 3, stan-

chions 4 supporting the roof, letter-board 5, upper and lower sashes 6 and 7 respectively, belt-rail 9, lower and fixed panels 10 and 11, and sills 12. All these parts have novel features, as will appear below.

The upper roof of the clear story 2 consists of an upwardly arched sheet 13, bounded on each of its edges by angle iron 14, secured by rivets 15, which also pass through correspondingly riveted angle irons 16, which extend transversely across the roof of the car to form rafters for the upper roof and against which the sheet 13 rests throughout the length of the rafters 16. The rafters 16 rest on longitudinal sills 17, preferably made of channel iron, which run throughout the length of the deck roof. The sills 17 are perforated adjacent to each rafter 16, and the lower web of each rafter 16 is slotted vertically for a little less than half its width and then bent at right angles to form the flange 18 which rests on the sill 17, and is riveted thereto by rivet 19, which passes through said perforation in the upper and horizontal web of the sill 17, and through a corresponding and registering perforation in the flange 18. As the clear story roof is the conventional shape, the rafters 16 and the sheet metal 13 are made to correspond.

The sill 17 is supported as shown in Fig. 5, by means of small angles 20, riveted by rivets 85 21 to the arch bars 22, which extend from one deck rail 23 to the other, and on to the walls of the car, as will appear below. The sill 17 is riveted by rivets 24 to the angle 20, which rivets pass through suitable perforations in the lower web of the channel iron 17 and the horizontal web of the angle plate 20. The arch bars 22 are made to rise vertically from deck rail 23 and then to curve inwardly and upwardly to the plate 13, against which they rest the greater portion of their length. Between these arch bars 22 are sashes 25, commonly known as ventilators. These sashes are supported from arch bars 22 by sheet metal plates 26, which extend from one deck rail 23 to the other, and which also extend to the sill 17, to which it is secured by rivets 27. The rivets 27 also secure angle plates 28 and a strip 29, which acts as a stop to limit the outwardly movement of the ventilators 25; to the strip 28 is secured the outer finishing sheet 30 in any suitable manner, which strip 30 extends from the lower roof 3 to the plate 13.

and this finishing strip 30 is suitably recessed to provide for ventilators. Rivets 31 hold this strip 30 in place. The arch bars 22 do not terminate at the deck rail 23, but are bent downwardly and outwardly to support the lower roof 3, and finally terminate at the eave-beam 32, and are fixed thereon by rivets. The arch bars 22 thus form carlines for the lower roof 3, and they are preferably made of channel iron, and are secured to the eave-beam 32 by rivets 33 (see Fig. 6). Their central webs terminate at this eave-beam and their other two webs are bent so as to rest flat on the upper horizontal web of this eave-beam 32, which is preferably a channel iron, similar in all respects to the channel iron 17 but somewhat larger in cross-section. On the carlines 22 rest longitudinally disposed wooden slats 34 which support the usual covering or sheeting 35 for the roof 3, as is customary in such structures. This sheeting 35 is secured at its lower edge by a screw 36, and its upper is extended under a wooden strip 37 over which the strip 30 is bent as shown in Fig. 12. Under the strip 30, and sandwiched in between it and the strip 37, is a sill sheet 38 on which the sash 25 rests, and which is bent upwardly and bent over the deck rail 23 and secured on the inside of the same by conduit strip 39, over which is an ornamental molding 40, which is preferably covered with metal and secured by screws 41. The conduit strip is held in place by means of bolts 42 extending therethrough.

In Fig. 13 is shown a spring actuated bolt 43, suitably mounted in the casing 44, fixed on the sheet metal 30 in any suitable way and so arranged that the bolt 43 is held in contact with a cam 45 fixed to the outside of the sash 25, which sash is pivoted, as shown in the dotted lines at 46, so that when the ventilator 25 is open, the spring bolt riding on the irregular cam 45 will hold this ventilator in any of several positions as desired.

Between the carlines 22, which extend from one side of the car clear to the other, as above described, are shorter and intermediate carlines 47, which extend from the eave-rail 32 through the deck rail 23, as is customary in such structures. Immediately below the carlines 22 are the posts 4, which will now be described. Each of these posts 4 is formed above two channel irons 48 and 49 respectively, 48 being the outer, and 49 the inner one, and these posts extend from the sill 12 to, the eave-beam 32. The outer channel 48 has its central web terminating at the lower edge of this eave-beam 32, and its other two webs are extended up to the lower edge of the upper horizontal web of this eave-beam 32, and secured thereto in any suitable manner, as by rivets 33 which also secure the carlines 22 in place. The precise manner of securing these webs together is not material, provided it is sufficiently strong. The channel iron 48

is extended down to the belt rail 9, where it is cut away to some extent to permit the intermediate I-beam 50 to pass through its extreme webs and then extends down below this and in rear of the plates 10 and 11 and is bent inwardly slightly above the plate 11, as shown in Fig. 16, and is firmly riveted to this plate by counter-sunk rivets and secured to the sill 12 in the same manner. The plate 11 is made very solid and firm so as to greatly strengthen and reinforce the sill 12, and the plate 10 is also secured by similar rivets 51. The channel 49 rests on the horizontal web of the sill 12 and is secured thereto by a suitable angle plate 52 and rivets 53, as shown in Figs. 16 and 20. In Fig. 21 is shown a similar structure, except that the channel beam is not as wide as shown in Fig. 20. The structure used at the end of the car where only one window is employed, may be made lighter than shown in Fig. 20, and in such a case the structure shown in Fig. 21 may be employed.

The channel 49 extends upwardly from the sill 12 and parallel with the channel 48, except where the same is curved inwardly above the plate 11, as referred to in the foregoing, and from this point on, the said channels 48 and 49 continue parallel until a point a little above the overlapping of the sashes 6 and 7 where the channel 49 curves inwardly and extends upwardly to the deck rail 23, where it is joined to the carlines 22 by having its central web cut away and its other two webs turned upwardly against the outer webs of the carlines 22, and to which they are secured by rivets 54, or by other suitable means. The channel irons 22 and 48 are also reinforced by crossed braces 55 which comprise sleeves 56, which fit in snug between the extreme flanges of the channel irons against the extreme flange, and are held in position by means of bolts 57 through said sleeves and passing through suitable perforations in irons 48 and 49. These channels 48 and 49 are similarly held in suitable relation by means of similar sleeves 58 secured by bolts 59, as shown in Fig. 17. As many of these braces are employed as may be necessary; 3 or 4 will be generally found sufficient for the purpose.

To the upper end of the channels 49 is secured a longitudinal wooden strip 60 by bolts or screws, or other suitable means, not shown, and below this are similar parallel strips 61 and 62 respectively. The strip 62 being located just above the curtain box, may be designated as a curtain rail, and the rail 61 as the basket rack rail. These three strips, 60, 61 and 62 are concealed by the usual head-lining 63. Secured to these rails by any suitable means, and outside of the head-lining are the usual upper and lower advertising molding 64 and 65, respectively, each of which is preferably of the usual form, except that it is made of a wooden filling with

a metal covering, so that no exposed wood-work appears in the finished car. The rail 62 may be secured as shown in Fig. 7 by plates 62^a riveted to the channel iron 49.

5 The curtain box 66 appears in the usual way below the curtain box rail 62, and below this is the usual molding 67, which is also metal covered, and from this runs the usual curtain groove 68, the outer wall of which is 10 formed by the metallic sheeting 69 bent into the form shown in cross-section in Fig. 17, and the channel 49 and the sheeting 69 is held in place by suitable screws 70 placed at the usual intervals. Above the belt rail 9 15 the channels 48 and 49 are also united by wooden strips 71 covered by metal sheeting 72 and metal parting strip 73. The wood 20 strip 71 is held in proper position by means of screws passing through perforations in the extreme webs of the channels 48 and 49 and into the wooden blocks 74 shown in dotted lines in Fig. 15. The screws 70 also extend into the same blocks. The outside parting strips 75 are preferably made of metal and 25 extend throughout the length of the windows. They are secured in place by means of screws 76.

The window sill 77 is preferably made of sheet metal and extends from one post 4 to 30 the next. Its lower edge is fixed by rivets or other suitable means, to the plate 10, from which it is extended upwardly and outwardly to above the I-beam 50; and then upwardly and outwardly in the usual form of window 35 sill to the sash 7, and then upwardly in the rear of the sash and inwardly in a horizontal direction to near the curtain groove 68.

The side lining 78 is disposed between the posts 4 in the usual manner, and extends 40 from the floor to the plate 77, under which it is bent to form the same depending flange 79 to give strength to the inner edge of the sheet 77. It is riveted to this sheet 77 by means of suitable rivets 80. The side lining 78 is 45 also secured by means of screws 81 to a wooden strip 82 fixed to the lower web of the I-beam 50, and below this, the strip 78 is reinforced by suitably and vertically disposed cleats 83, which are preferably covered 50 with metal as shown. These cleats 83 form the supports for the seats, and run downwardly from the wooden strip 82 toward the floor. The lower edge of the sheet 78 has a suitable angle 84, and a similar one 85 is 55 placed higher up. The angle 84 reinforces the lower edge of the sheet 78, and the upper one assists in supporting the seat cushion.

The flooring of the car is not shown, nor are the intermediate sills and the crossings, 60 the platforms and ends of the car. As these may be of any suitable construction, a detailed description of them is unnecessary.

The sashes 6 and 7 are supported in the manner shown and described in the Bucknam 65 patents, Nos. 300,717 and 801,508, respec-

tively. That is, the upper sash 6 is hung from rails 88, secured to the deck rail 23 by bolts 89 near their upper ends, and at their lower by screws 90 in the letter-board 5. The channels 32 are recessed at 91, so as not to interfere with the movement of the hangers (not shown) to which the sash 6 is secured. On this sash 6 are also the flanges for guiding the lower sash 7, precisely as in said Bucknam patents. These sashes raise between 75 the inner parting strip 74 and the outer parting strip 75, precisely as set forth in the Bucknam patents. To make a tight joint, the upper and outer edge of the sash 6 rubs against brass weather strips 92 secured to 80 the inside of the letter-board 5 at the top of the window.

As shown in Figs. 17 and 18, the I-beam 50 is held to the stanchions 4 by means of angles 100 and rivets 101. The outer webs 85 of the beam 50 are cut away at 102 to permit the channel 48 to pass uninterruptedly, and the channel 49 is recessed at 103 to permit the beam 50 to rest thereon.

From the foregoing it is evident that my 90 improved car, as above described, is rigid, durable and is as light as is consistent with said rigidity and durability. It is also evident that my invention is not limited to the precise details of construction, but that it is 95 broad enough to cover all equivalent structures that come within the scope of the annexed claims.

What I claim is:

1. In a car or similar device, stanchions, 100 eave-beams supported by said stanchions, channel iron carlines extending from one eave-beam to the other, said carlines having their central webs cut away and the extreme webs extended laterally, and means for securing 105 said laterally extending ends to the eave-beam.

2. In a car or similar device, stanchions, eave-beams supported by said stanchions, channel iron carlines extending from one 110 eave-beam to the other, said carlines having their central webs cut away and the extreme webs extended laterally, and means for securing the laterally extending ends to the eave-beam, a deck rail secured to said carlines and 115 an upper and a lower roof supported by said carlines.

3. In a car or similar device, eave-beams, carlines extending from one eave-beam to the other, upper and lower roofs supported by 120 said carlines, a deck rail secured to said carlines, angles fixed to said carlines, channel irons fixed to said angles, and rafters resting on said channel irons whereby said rafters 125 coact with said carlines to support the upper roof.

4. In a car, eave-beams, carlines secured thereto and extending across the roof of the car, deck rail fixed to said carlines, angles fixed to said carlines, sills resting on said an- 130

- gles and secured thereto, rafters supported by said sills, a clear story roof resting on said rafters, and sheet metal plates covering the inner surfaces of said carlines and rafters.
5. In a car, an upwardly arched clear story roof, angles secured to the edges of said roof, angle metal rafters extending under said roof, each of said rafters having its lower web slitted to about midway of its breadth 10 and then having a portion bent laterally of the web, a sill on which said laterally extending portion rests, and means for holding said sill and rafter together.
6. In a car or similar device, an upwardly arched clear story roof and rafters supporting same, a sill on which said rafters rest and to which they are secured, angle metal sheets secured to the lower and outer edges of said sills, a lining secured to said angle metal 20 plates, a strip secured to said lining, and a ventilator window pivotally mounted below said sill and adapted to rest against said strip.
7. In a car or similar device, carlines, an upper and a lower roof supported thereby, a 25 deck rail, ventilators pivotally mounted between the upper and lower roofs, a cam fixed to the outer surface of each of said ventilators and a spring actuated bolt engaging said cam and adapted to hold said ventilator 30 in any of several positions.
8. In a car or similar device, carlines extending from one side of the car to the other, and said carlines being so bent as to support the upper and lower roofs of said car, ventilators, a deck rail secured by suitable angles and rivets to said carlines, and a sheet metal 35 sill secured to said ventilator and extending between said carlines.
9. In a car or similar device, channel irons, carlines, a ventilator rail secured to said carlines by means of angles, a sheet metal window sill for the ventilators extending between the carlines and over the ventilator rail, a conduit secured to said ventilator rail 40 and over the end of said sill sheet and an ornamental molding covering said conduit strip.
10. In a car or similar device, an eave-beam, channel iron carlines extending therefrom and secured thereto, stanchions fixed to said eave-beam immediately under said carlines, each of said stanchions comprising two channel irons, one of which extends vertically to the eave-beam and the other of which 45 bends upward and inwardly and joins said carlines at the deck rail, and means for securing the said parts together.
11. In a car or similar device, a carline formed of channel iron and extending upwardly and inwardly to a deck rail, and eave-beam and a stanchion composed of two channel irons, one of which runs to said eave-beam and rests immediately under said carline, and the other of which runs upwardly 55 and inwardly and joins said carline at the deck rail, and a brace uniting said carline and stanchion.
12. In a car, an eave-beam, carlines formed of channel iron and extending upwardly and inwardly from said beam, a deck rail secured to said carlines, a stanchion below each of said carlines provided with two channel irons, one of which is fixed to said eave-beam below 70 said carline, and the other of which extends upwardly and inwardly to said carline and 75 deck rail, a brace connecting said channel iron and last mentioned carline, and a head-lining supported by said last mentioned channel iron of the stanchion.
13. In a car, an eave-beam, carlines formed of channel iron and extending upwardly and inwardly from said beam, a deck rail secured to said carlines, a stanchion below each of said carlines provided with two channel irons, one of which is fixed to said eave-beam below 80 said carline, and the other of which extends upwardly and inwardly to said carline and 85 deck rail, a brace connecting said channel iron and carline, a head-lining supported by said last mentioned channel iron, and a basket 90 rack rail carried by said channel iron and to which said head-lining is secured.
14. In a car, an eave-beam, carlines formed of channel iron and extending upwardly and inwardly from said beam, a deck rail secured 95 to said carlines, a stanchion below each of said carlines provided with two channel irons, one of which is fixed to said eave-beam below said carline, and the other of which extends upwardly and inwardly to said carline and 100 deck rail, a brace connecting said channel iron and carline, a head-lining supported by said last mentioned channel iron, a basket 105 rack rail carried by said channel iron and to which said head-lining is secured, and a curtain rail concealed by said head-lining and 110 secured to said stanchion.
15. In a car, a stanchion composed of two channel irons having their extreme webs in the same vertical plane and extending 110 toward each other, the outer of said channel irons extending substantially vertical from the eave-beam to the lower sill of the car, and the other of said channel irons running parallel with the outer channel iron to near the 115 eave-beam and then bending inwardly and upwardly to the deck rail, and a brace for securing said channel irons together.
16. In a car, a stanchion composed of two channel irons having extreme webs in the same vertical plane and extending toward each other, the outer of said channel irons 120 extending substantially vertical from the eave-beam to the lower sill of the car, and the other of said channel irons running parallel 125 with the outer channel iron to near the eave-beam and then inwardly and upwardly to the deck rail, a brace for securing said channel irons together, and sheet metal strips covering portions of said channel irons. 130

17. In a car, a stanchion composed of two channel irons having extreme webs in the same vertical plane and extending toward each other, the outer of said channel irons 5 extending substantially vertical from the eave-beam to the lower sill of the car, and the other of said channel irons running parallel with the outer channel iron to near the eave-beam and then inwardly and upwardly to the 10 deck rail, a brace for securing said channel irons together, sheet metal strips covering portions of said channel irons, and wooden strips covered by said sheet metal strips.
18. In a car or similar device, a number of 15 stanchions, each comprised of inner and outer channel irons, said channel irons running substantially parallel throughout the greater portion of their lengths, and the outer channel iron being vertically disposed to the eave- 20 beam, the inner channel iron curving upwardly and inwardly near the eave-beam and extending to the deck rail, means for holding said channel irons in their relative positions, and lower panels fixed to said channel irons.
19. In a car or similar device, a number of 25 stanchions, each comprised of outer and inner channel irons, said channel irons running substantially parallel throughout the greater portion of their lengths, and the outer channel 30 being vertically disposed to the eave-beam of the inner channel iron curving upwardly and inwardly near the eave-beam and extending to the deck rail, means for holding said channel irons in their relative positions, lower panels fixed to said channel irons, and lower sills secured to said stanchions and 35 panels.
20. In a car or similar device, a number of 40 stanchions, each composed of outer and inner channel irons, said channel irons running substantially parallel throughout the greater portion of their lengths, the outer channel iron being vertically disposed to the eave-beam of the inner channel iron curving upwardly 45 and inwardly to the eave-beam and extending to the deck rail, means for holding said channel irons in their relative positions, lower panels fixed to said channel irons, and belt rail secured to said stanchions and upper 50 panel.
21. In a car or similar device, a number of 55 stanchions, each comprised of outer and inner channel irons, said channel irons running substantially parallel throughout the greater portion of their lengths, and the outer channel iron being vertically disposed to the eave-beam curving upwardly and inwardly near the eave-beam and extending to the deck rail, means for holding said channel irons in
- their relative positions, lower panels fixed to 60 said channel irons, lower sills secured to said stanchions and panels, and an I-beam connecting said stanchions.
22. In a car or similar device, a number of 65 stanchions, each comprised of outer and inner channel irons, said channel irons running substantially parallel throughout the greater portion of their lengths, and the outer channel iron being vertically disposed to the eave-beam of the inner channel iron curving up- 70 wardly and inwardly near the eave-beam and extending to the deck rail, means for holding said channel irons in their relative positions, lower panels fixed to said channel irons, lower sills secured to said stanchions and 75 panels, and angle plates fixing said stanchions and sills together.
23. In a car or similar device, a stanchion composed of two channel irons, an outer and an inner, an I-beam passing through said 80 stanchion, the inner channel being recessed to permit the beam to pass through and the beam being recessed to permit the outer channel to pass therethrough, and angles secured to said channel irons and I-beam. 85
24. In a car or similar device, a stanchion composed of two channel irons and means for holding said channel irons in their proper relative positions, an I-beam, a window sill plate fixed to said stanchion and extending over said I-beam, and a side lining adjacent to said stanchion and provided with a depending upper edge to reinforce said window sill. 90
25. In a car or similar device, a stanchion 95 composed of two channel irons and means for holding said channel irons in their proper relative positions, an I-beam, a window sill plate fixed to said stanchion and extending over said I-beam, a side lining adjacent to 100 said stanchion and provided with a depending upper edge to reinforce the said window sill, and side supports secured to said side lining.
26. In a car or similar device, a number of 105 stanchions, each of which is composed of channel irons with means of uniting the same and holding them in their proper relative positions, one of said channel irons being provided with a slightly inset lower portion 110 to which a rigid lower panel is secured, and a second panel secured to and overlapping said lower panel and also secured to said channel.

Signed the 13th day of September, 1906.
WARREN M. SMITH.
